UNITED STATES PATENT OFFICE.

RUTGERS STAGG KASSON, OF KEESEVILLE, NEW YORK.

BROODER.

1,310,348.

Specification of Letters Patent. Patented July 15, 1919.

Application filed August 29, 1916. Serial No. 117,440.

To all whom it may concern:

Be it known that I, RUTGERS STAGG KASSON, a citizen of the United States, and a resident of Keeseville, in the county of Essex and State of New York, have invented a new and Improved Brooder, of which the following is a full, clear, and exact description.

My invention in its present form is more particularly designed for embodiment in a brooder having a coal stove, though the invention is not limited in all its features to the use of a coal stove.

The nature of the invention and the advantages of the structural embodiment given as an example will be understood from the following description.

Reference is to be had to the accompanying drawings forming a part of this specification in which similar reference characters indicate corresponding parts in all the views.

Figure 1 is a transverse vertical section of a brooder and its heater;

Fig. 2 is a plan view with the hover omitted;

Fig. 3 is a horizontal section on the line 3—3, Fig. 1;

Fig. 4 is a transverse vertical section on the line 4—4, Fig. 2;

Fig. 5 is a perspective view of the brooder on a reduced scale.

In the illustrated example of my invention a stove body 10 of a suitable type is employed, the body shown being in general of a well known form. The body is provided with a base 11 to receive an ash pan, the ash box being closed by a door 12, and, in the preferred form, supported on a stand 13 secured by stove bolts 13^a to the annular flange 10^a of the stove body.

An arcuate water trough 14 may be provided on the stove body to receive water for maintaining the proper degree of humidity.

The hover includes a curtain 15 depending from a flat top 16. The top is formed in sections as hereinafter explained and the sections may be provided with reinforcing strips 17 at the under side. The hover is supported on the stove body 10 for which purpose a super-structure is secured to the top of the stove. Said super-structure advantageously is in the form of a ring 18 secured by bolts 19 which pass through an inturned flange 20 on the upper edge of the ring and through the top 21 of

the stove. The ring at the bottom, at intervals, is provided with angular depending flanges 22 to fit over the stove at the angle formed by the sides and top.

The top 16 of the hover rests, in the preferred form of the invention, directly on the top of the ring 18. In order to provide an increased support for the hover, radial arms 23 are provided and detachably engage with the ring 18. Each arm, at its inner end, has an upturned hook 24 which projects through a slot 25 in the ring so that the upper end of the hook engages the inner surface of the ring above the said slot. On each arm 23 at 70 the base of the hook 24, lugs 26 are cast to bear against the outer surface of the ring 18 at each side of a slot 25. The arrangement serves to support the arms 23 with the upper surfaces thereof flush with the upper surface of the ring 18.

The sections of the top 16 of the hover are connected by hinges 27 to permit the front section to be raised whereby to afford access to the lid 29 covering the fuel opening 28, 80 said lid being pivotally mounted, preferably by horizontal trunnions 29^a to swing upwardly. The height of the ring 18 and the positions of the trunnions 29^a are such as to permit the lid to have clearance beneath the 85 hover top 16.

The line of the hinges 27 is determined by the stove pipe or flue 30 which is located near the rear of the stove top, and which extends through the fixed section of the hover top and therefore, the hinge line will always be disposed in the same direction, for which reason I am enabled to provide a fuel opening 28 of oblong form centrally positioned in the stove top, and of ample capacity to 95 readily receive the coal from a shovel directed rearwardly from the front of the stove. The major axis of the oblong opening is disposed in the same direction as the hinges 27 and therefore, the user will naturally be prompted to direct the coal to the fuel opening from the front of the stove, from which direction the oblong opening is particularly advantageous to readily receive a reasonable charge of coal from a shovel.

A smoke outlet 31 is formed in the stove top rearward of the fuel opening, and in order to provide a simple and efficient check draft, a box 32, generally rectangular, is secured to the stove top over the outlet 31 110 by means of bolts or screws 32^a, said box having a round collar 33 cast thereon at the

top to receive the stove pipe 30. In the back of the box 32 is a vertical check draft opening 34, controlled by a check draft damper 35 mounted on horizontal pivots as at 36, 5 (Fig. 1).

It is to be observed that the check draft opening 34 is within the hover, that is to say, beneath the hover top 16. The check draft 35 is thermostatically controlled and 10 therefore, when the same is opened to admit air to the box 32 and stove pipe 30, thereby checking the draft through the opening 31, the air admitted to the stove pipe will be the hot air taken from the interior of the 15 brooder at the top. I thus immediately reduce the temperature of the air in the brooder instead of being solely dependent on the cooling of the stove, so that the chicks are thus promptly relieved of the excessive 20 heat immediately upon the operation of the thermostat. In order that air may freely pass to the check-draft opening 34 from all sides of the brooder, the ring 18 is formed with side openings 18^a at various points so 25 that air may pass into the ring 18 from all directions to finally escape at the opening 34.

The check-draft damper 35 has a hooked arm 37 projecting from the back thereof 30 through the adjacent opening 18^a in the ring 18 and receives the rod 38 leading from the thermostat, designated generally by the numeral 39, which may be of any well known type. The thermostat illustrated preferably 35 includes a pair of diaphragms, 40, and relatively fixed and movable arms hinged at the outer ends as at 41. A screw 42 preferably having thumb wings on the head thereof is threaded into and extends through the upper arm and bears against the lower arm to 40 adjust their relation. The fixed arm is secured to the stove in any suitable manner as by stove bolts 45. The rod 38 connects with the lower arm of the thermostat at 43 and 45 extends upwardly through an opening 44 in the fixed arm.

The fuel lid 29, it will be observed from Fig. 2, has the lifting knob 46 thereof disposed nearer to one end than to the other 50 and thereby said knob will clear the box 32 and permit the lid 29 to be supported in inclined position against the said box 32.

The described construction enables me to provide an ample fuel opening in the top of 55 a brooder stove of the type illustrated, and to do this is exceedingly difficult owing to the comparatively small area of the stove top and because of the space taken up by the flue and check draft devices. At the same 60 time the construction promotes simplicity and convenience in the check draft devices.

I provide in the base of the stove a non-variable draft inlet beneath the grate and of predetermined limited capacity, for 65 which purpose holes 47 are produced in the

base preferably disposed vertically and located at the front above the ash door 12. Said ash door 12, I make without openings in order that when in place, it will effect a complete closure of the ash box except for 70 the provision of the non-variable air holes 47, which latter, therefore, form the sole means for the admission of air beneath the grate 48. The draft inlet therefore is wholly independent of the thermostatic control of the stove through the check-draft. The capacity of the inlet openings 47 is such as to supply the right amount of air to the stove for promoting combustion when the draft through the opening 31 is unchecked 80 and is also ample to admit sufficient air for sustaining the combustion when the check draft is opened.

Having thus described my invention I claim as new, and desire to secure by Letters 85 Patent:

1. In a brooder, a stove having a draft outlet in the top thereof, a box on the stove at said outlet, said box having a collar at the top to receive a stove pipe, and the box forming a flue passage establishing communication between said draft outlet and said stove pipe collar, and having a check draft opening below the collar, a super-structure on the stove additional to said box, a hover supported on said super-structure above said check draft opening so that the interior of the hover may be in communication with the said check draft opening, and means to open or close said check draft opening to establish or disestablish communication between the interior of the hover and the check draft opening, without affecting the communication between the said draft outlet in the stove top and the said flue passage and without affecting communication between the said flue passage and collar.

2. In a brooder, a stove having a draft outlet opening in the top thereof, a box on the stove at the said opening, said box having a collar at the top to receive a stove pipe, and having a check draft opening below said collar, a movable closure for said check draft opening, a ring on the stove at the top and rising therefrom above the check draft opening, and outside of the said box, and a hover having the top thereof supported on the top of the said ring, the said check draft opening establishing communication between the interior of the ring and the said box, the said ring having openings therein to admit air from beneath the hover in various directions to the said check draft opening through the said ring.

3. In a brooder, a stove having a draft outlet opening in the top, a box on the stove rising from the top thereof at the said opening, said box having a collar thereon to receive a stove pipe, and having a check draft opening below said collar above the stove

top, a movable closure for said check draft opening, a separate ring on the stove top and extending outside of said box, said ring rising from the stove top to a height above 5 the said check draft opening, said closure having an arm extending outwardly therefrom through the said ring, and the ring having an opening to admit air therethrough to the check draft opening, thermostatically actuated means connected with the said arm, 10 and a hover having the top thereof above the said openings and supported by said ring.

4. In a brooder, a stove, a ring on the stove at the top and rising therefrom, a 15 hover having the top thereof covering the said ring, a series of arms detachably connected with the said ring and extending radially beneath the hover top to afford support to the same, said stove having a 20 draft outlet in the top, a box on the stove top at the said outlet opening within the ring, said box having a check draft opening, and the ring having an opening to admit air from the interior of the hover to the 25 check draft opening, and a damper controlling said check-draft opening.

5. In a brooder, a stove, a hover, means to support the hover above the stove top, said stove top having an oblong fuel opening, a 30 lid for said oblong opening, a structure on the stove top at the back of the fuel opening adapted to receive a stove pipe, the said hover being formed of a relatively fixed section and a hinged section, said relatively 35 fixed hover section having a hole therethrough for the passage of a stove pipe, the major axis of the oblong fuel opening corresponding in direction with the line of the hinge connection of the hover sections, said 40 lid being rockably supported on the stove top to swing in a vertical plane beneath said fixed hover section from a closed position toward said stove-pipe supporting structure.

6. In a brooder, a stove, a hover, means on 45 the stove and rising above the top thereof, supporting said hover spaced from the stove top, the said stove top having a central oblong fuel opening, and having a draft outlet near the back of the said stove top, a box 50 on the stove top at said outlet, a collar on the box to receive a stove pipe, the said box having a check draft opening, means to control said opening, an oblong stove lid rockably mounted on the stove top to swing to and 55 from the said box, and a knob on the stove

lid between the center and one end of the lid to clear the said box and permit the lid to rest against the latter, the said hover being formed in sections, the rear section being relatively fixed and having a hole there- 60 through for the passage of a stove pipe and being at an elevation above the stove top to permit swinging of the stove lid, the front section being adapted to be raised and lowered to afford access to the fuel opening, the 65 major axis of the said fuel opening corresponding in direction with the axis of the hinge means of the hover.

7. In a brooder, a stove, a hover, means on the stove and rising above the top thereof 70 supporting said hover spaced from the stove top, the said stove top having a central oblong fuel opening, and having a draft outlet therein near the back of the said stove top, a box on the stove top at said outlet, a 75 collar on the box to receive a stove pipe, the said box having a check draft opening in the rear side thereof, means to control said opening, an oblong lid for the fuel opening pivotally mounted on the stove top to swing upwardly against the front of said box, the said hover being formed in sections, the rear relatively fixed section being at an elevation to afford clearance for the swinging 80 of the stove lid and having a hole there- 85 through for the passage of a stove pipe, the front section being adapted to be raised and lowered to afford access to the fuel opening, the major axis of the fuel opening corresponding in direction with the axis of the 90 hinge means of the hover.

8. In a brooder, a stove body having a flue at the top and a check draft in the flue, a stove base having an ash door opening, and an ash door having no draft opening and 95 forming when in place a complete closure of the said ash door opening, the said base having a constantly open, invariable, uncontrolled draft inlet independent of said ash door opening and of predetermined limited 100 capacity; together with a thermostat controlling said check draft without affecting the said draft inlet and without affecting communication between the stove and flue, said draft inlet being in free communication at all times with the interior of the hover both when the check draft is open and when said draft is closed.

RUTGERS STAGG KASSON.
